UNITED STATES PATENT OFFICE.

HOMER L. ROGERS, OF HARTWELL, OHIO, ASSIGNOR TO THE PHILIP CAREY MANUFACTURING COMPANY, A CORPORATION OF OHIO.

SYSTEM OF TRACK INSTALLATION.

Application filed March 1, 1926. Serial No. 91,420.

My invention relates to a system of track installation in which the track is insulated so that the transmission of the vibration or movement of the track rail, due to passage of cars over it, to surrounding structures is minimized or prevented. I am able by my invention to install tracks using either wood, metal, concrete or other ties to which the rails are attached. I provide a suitable material, in contact with the rails of the track, which is of such a character that while sufficiently solid and rigid, to withstand shock or stresses due to traffic over the rail and to permit of being readily handled and transported, is likewise sufficiently plastic, elastic or flexible to absorb the shocks and vibration without transmitting them to the adjacent structure. In this way I not only preserve the surrounding structure against the strains due to vibration and shock from the traffic but also provide means for permitting movement of the rail or the surrounding structure due to temperature changes without damage to the tracks or the structure adjacent thereto thereby greatly reducing the expense of repairs, and reducing noise. I preferably use in my track insulation an insulating material which in addition to the qualities stated is also of such a character that it prevents transmission of electricity from or to the rail—is preferably also of such a character that it serves to water proof or moist proof the tracks or surrounding structure from water or moisture and of sufficient adhesiveness to adhere to the rail and prevent access of foreign matter to same.

In the drawings Figure 1 is a cross section of a rail showing my system of track installation. Figure 2 is a side view of Figure 1 and Figure 3 is a cross section of a modification of Figure 1 showing a slightly different type of rail. In the drawings in which like characters refer to like parts 2 and 3 are rail fillers and 4 is a rail pad or cushion which are all constructed preferably of a bituminous material such as asphalt containing an intimate mix forming a homogeneous mass of fibrous materials or solid materials or both to give it the required rigidity as stated. The filler 2 has longitudinal grooves or recesses to assist in keying it to adjacent construction. The filler 3 is likewise provided with keys for the same purpose. These fillers are preformed to conform to

the contour of the portion of the rail into which they are placed and should preferably completely fill that portion so as to be in intimate contact with that portion of the rail. If desired the filler portion that is to contact with the rail, or the rail, may be coated with asphalt or other bituminous material, or a material that will act as a solvent of the filler material may be applied to the surface of the filler, so as to cause adhesion of the filler to the rail. The cushion 4 is preferably made in the form of a longitudinal channel, the sides 4^a of which extend upward and over the base plate of the rail and are in intimate contact, and preferably in adhesive contact, with the rail fillers 2 and 3. In this manner I am able to surround or envelop the rail on all sides except the wheel surface thereof. These cushions 4 may be placed the full length of the rail as shown with the spikes or bolts, which hold the rails to the ties, passing through the cushion 4, or may if desired be placed below the rail only between the cross ties so that the rail rests on the cross ties and between the cross ties on the cushion. I prefer however to have the cushions below and in contact with the entire length of the rail as it enables me to get a more complete insulation. In Figure 3, I have shown a modification of rail filler being cored and a modified type of rail.

With the rails of the track installed as above described I have found that not only is the expense of maintenance greatly reduced but the noise of passing cars is muffled by the absorption of the vibration of the rails. The filler blocks have their surfaces which are adjacent to the surrounding construction, which may be concrete, stone or wood blocks or any suitable construction, arranged preferably vertical, i. e., parallel to the rail web. When this adjacent construction is concrete I prefer to use the filler blocks provided with the key way as shown.

Claims:

1. A system of track installation consisting of a rail, preformed blocks of vibration absorbing bituminous material conforming to the contour of portions of the rail so arranged as to surround the rail on three sides thereof.
2. A system of track installation consisting of a rail, preformed vibration absorbing

bituminous material conforming to the contour of portions of the rail so arranged as to surround and intimately contact with the rail on three sides thereof.

5. 3. A system of track installation consisting of a rail, preformed blocks of a bituminous material arranged on opposite sides of and in contact with said rail, a preformed cushion of bituminous material below the base of 10 and in contact with the rail, said blocks and said cushion in contact with each other.

15. 4. A system of track installation consisting of a rail, preformed blocks of a bituminous material arranged on opposite sides of and in contact with said rail, a preformed cushion of bituminous material below the base of and in contact with the rail, said blocks and said cushion in adhesive contact with each other.

20. 5. A system of track installation consisting of a rail, preformed blocks of a bituminous material arranged on opposite sides of and in contact with said rail, a preformed cushion of bituminous material below the base of 25 and in contact with the rail, said blocks and said cushion in adhesive contact with each other, all so arranged as to surround said rail except the wheel surface thereof.

6. A system of track installation consisting

of a rail, blocks of a waterproof non-deteriorating vibration absorbing material, preformed to conform to the size and formation of portions of said rail and arranged in intimate adhesive contact with said portions, a cushion arranged below the base of said rail, said blocks and said cushion insulating said rail from the surrounding construction.

7. A system of track installation consisting of a rail, blocks of a waterproof non-deteriorating vibration absorbing material, preformed to conform to the size and formation of portions of said rail and arranged in intimate contact with said portions, a cushion arranged below the base of said rail, said blocks and said cushion in adhesive contact with each other and insulating said rail from the surrounding construction.

8. A system of track installation consisting of a rail, preformed blocks of bituminous material arranged on opposite sides of and in contact with said rail, a preformed cushion containing a bituminous material provided with a portion adapted to lie below the base of the rail and a portion extending upward along the side of the base plate of the rail.

In testimony whereof, I have signed my name to this specification.

HOMER L. ROGERS.
